UNITED STATES PATENT OFFICE.

FRELING C. FOSTER, OF CHICAGO, ILLINOIS, ASSIGNOR TO THE UNION
TYPE FOUNDRY, OF SAME PLACE.

DESIGN FOR A FONT OF PRINTING-TYPE.

SPECIFICATION forming part of Design No. 18,627, dated September 25, 1888.

Application filed August 13, 1888. Serial No. 282,661. Term of patent 3½ years.

To all whom it may concern:

- Be it known that I, FRELING C. FOSTER, a citizen of the United States, residing at Chicago, in the county of Cook and State of Illinois, have invented and produced a new and original Design for a Font of Printing-Type, of which the following is a specification, reference being had to the accompanying stereotype print, forming part thereof.
- 5 My design consists of a font of printing-type consisting of large capital letters of "old-style" type, the characteristic feature of which is the heavy shaded vertical lines and the light unshaded horizontal lines.
- 10 The letters A and H have two light curved cross-lines, the former having also a truncated peak. B, P, and R have a light slanting middle joining-line. C, E, F, G, L, S, T, and Z have slanting shade lines or points. In the letters E and F the vertical lines are unequally divided by the intermediate horizontal lines. J and & have light spiral flourish with terminal dot.
- 15

What I claim, and desire to secure by Letters Patent, is—

The design for a font of type of capital letters having heavy shaded vertical lines and light unshaded cross-lines at irregular heights and slanting shade lines or points, substantially as shown and described.

FRELING C. FOSTER.
